[57] CLAIM

The ornamental design for combined handle and es-
cutecheon with lock, as shown and described.

DESCRIPTION

FIG. 1 is a perspective view of a combined handle and
escutcheon with lock showing my new design;
FIG. 2 is a front elevational view thereof;
FIG. 3 is a reduced rear elevational view thereof;
FIG. 4 is a reduced right side elevational view thereof;
FIG. 5 is a reduced top plan view thereof;
FIG. 6 is a reduced bottom plan view thereof;
FIG. 7 is a reduced left side elevational view thereof.
The indicia shown in broken lines in FIGS. 1 and 2 is for
illustrative purposes only.

FIG. 1

FIG. 2
